UNITED STATES PATENT OFFICE.

ORREN E. MASSEY AND ORREN W. MASSEY, OF MACON, GEORGIA.

CONDENSER FOR COTTON-GINS.

SPECIFICATION forming part of Letters Patent No. 233,785, dated October 26, 1880.

Application filed June 23, 1880. (No model.)

To all whom it may concern:

Be it known that we, ORREN E. MASSEY and ORREN W. MASSEY, of Macon, in the county of Bibb and State of Georgia, have 5 invented certain new and useful Improvements in Condensers for Cotton-Gins; and we do hereby declare the following to be a full, clear, and exact description of the invention, such as will enable others skilled in the art to which 10 it pertains to make and use it, reference being had to the accompanying drawing, which forms part of this specification.

Our invention relates to an improvement in condensers for cotton-gins; and it consists in 15 the combination of a single solid fluted or grooved roller with a wire screen, the roller and screen being made to revolve in opposite directions, so as to catch the cotton between them, and thus avoid the necessity of two rollers for the purpose of compressing the cotton.

It further consists in the use of a fluted or grooved roller which slightly compresses the cotton as it passes through the condenser, as will be more fully described hereinafter.

25 The object of our invention is to condense or bat the cotton as it passes from the gin, just sufficiently to make it adhere nicely together, without compressing it to such an extent as to spoil the sample, as is always the case where 30 two solid rollers are used.

The accompanying drawing represents a vertical section of our invention.

A represents the frame of our condenser, which is provided with the hinges B, so that 35 it can be hung directly over the flue of the gin, and thus receive the ginned or lint cotton as rapidly as it passes from the gin. Upon the opposite end of this frame A from where it is hung upon the gin, the frame is provided with a suitable door, C, which opens upward, so as to give 40 access to the interior of the frame at any time. Journaled in this frame is the revolving wire screen D, which may be either open or closed at its ends, as may be preferred. As the ginned 45 or lint cotton passes over the top of this revolving screen the dust and dirt contained in the cotton will drop down through the meshes in the screen upon the floor. Where the ends of the revolving screen are left open this dirt and 50 dust escapes much more readily through the

open ends than it does when the ends are closed. Suspended from the lower edge of this frame, by means of wires or any other suitable device, is the apron F, which has its lower edge tacked to the floor, and which serves to separate the 55 dirt and dust which drops through the cylinder from the cotton after the cotton has been condensed. Were it not for this apron the cotton, as it drops from the end of the frame, would be apt to fall upon the dirt and dust on 60 the floor, and thus become dirty.

Journaled in the lower outer corners of the frame A is the fluted or grooved condensing-roller G, which does not come in contact with the revolving screen, but does revolve in an 65 opposite direction from the screen, so as to cause the cotton to pass in between the two. This roller is grooved or fluted, as shown, so that it will act upon the cotton only at certain regular intervals, and for the purpose of cleaning the screen more perfectly.

As the fiber of the cotton is always long enough to make the cotton adhere together it is only necessary that the cotton should be 75 slightly condensed, and it will adhere together sufficiently well to form a bat without the danger of condensing the cotton to such an extent that the sample will be spoiled. All that is needed is simply to have the cotton adhere together in the form of a long sheet or bat, and 80 when the ginned cotton is passed between two solid rollers for the purpose of condensing it too much pressure is brought to bear upon the cotton, and hence the sample is more or less spoiled. By grooving this roller so that 85 it condenses the cotton only at certain intervals, just as good and perfect a bat is formed, and that without condensing the cotton to any great extent. Upon one of the ends of this grooved condensing-roller is placed a driving-pulley, J, and a pinion, Q. This pinion meshes with the gear-wheel P on the shaft which 90 passes through the revolving screen, and hence the roller and the screen are made to revolve in opposite directions, so as to catch the cotton as it passes over the screen and cause it to pass down between them. Inside of the frame suitable flexible guards are placed over the ends of the screen and the sides of the 95 screen and roller, so as to prevent any of the 100

cotton from catching in between them and the sides of the frame.

By journaling the shaft or bearings of the grooved roller in the sides of the frame, as hereshown, all need of boxes is dispensed with.

At the lower outer corner of the frame A are formed brackets, in which the shaft of the roller G revolves, and thus the use of boxes is dispensed with.

- 10 We are aware that a roller having its surface formed into a series of small grooves with practically no space between them has heretofore been used, and this we disclaim. As will be seen, in our roller there is a considerable space
15 between each pair of grooves or recesses, and this space is absolutely necessary to compress the cotton so that it will remain in that condition. Where there is practically no space between the grooves enough of the cotton is not
20 acted on at a time to cause the fibers to adhere.

Having thus described our invention, we claim—

The combination of the frame A, adapted to be hung upon one end of the cotton-gin, the wire screen D, having the gear-wheel P secured to one end of its shaft, and the grooved condensing-roller G, having the pinion Q upon one end of its shaft, the roller and screen being made to revolve in opposite directions and to condense the cotton at intervals between them, substantially as shown and described.

In testimony that we claim the foregoing we have hereunto set our hands this 18th day of June, 1880.

ORREN E. MASSEY.
ORREN WEBB MASSEY.
